MOLD CHARGE DELIVERY APPARATUS

George E. Rowe, Wethersfield, Conn., assignor to
Hartford-Empire Company, Hartford, Conn., a
corporation of Delaware

Application June 10, 1932, Serial No. 616,392

4 Claims. (Cl. 49—14)

This invention relates to improvements in apparatus for guiding or directing separated charges of molten glass to the molds of a glass-ware forming machine.

- 5 In my prior application, Ser. No. 521,688, filed March 11, 1931, I disclose apparatus for feeding molten glass, including a substantially vertical charge guide having a back wall and a pair of opposed side walls extending at substantially 10 right angles with the back wall. This charge guide of my aforesaid prior application is open not only at its upper and lower ends, but at its front, and the side walls thereof are adjustable with relation to each other.
- 15 The charge guide of my prior application is supported by suitable adjusting and operating mechanism whereby it may be accurately aligned with a feeder outlet and with a mold to be charged, and may be moved in register with the 20 mold during the charging of the latter.

An object of the present invention is to improve a charge guide of the general type of that disclosed in my prior application, that is, a substantially vertical charge guide having a back 25 wall and spaced opposed side walls extending at substantially right angles with the back wall, by providing simple and efficient means for maintaining the walls of the charge guide at a substantially uniform desirably low temperature, and for effecting a more positively controlled movement of a charge through the guide and centrally into a mold that is to be charged.

A further object of the invention is to provide 30 a charge guide of the general character above referred to with a readily attachable and removable means for preventing any forward deviation from a desirable right-line path of movement through the guide of any portion of a charge that is being guided and directed to an 40 underlying mold.

A further object of the invention is the provision 45 in a charge guide of the general character above referred to of a simple, reliable and efficient means at the front of the guide for applying fluid under pressure to the inner walls of the guide and to the charge that is passing therethrough for cooling and lubricating the walls of the guide and for preventing forward deflection of any portion of the charge from the path of 50 movement required to deliver the charge axially and centrally into an underlying mold.

A further object of the invention is to improve 55 a charge guide of the general character above referred to by providing improved means for adjustably connecting the side walls of the

guide with the back portion thereof to permit convenient and easy adjustment of the side walls with respect to each other without disassembly or loosening of the parts of the guide.

Other objects and advantages of the invention 60 will become apparent from the following description of a specific embodiment of the invention, particularly when such description is considered in conjunction with the accompanying drawing, in which

65 Figure 1 is a view, mainly in side elevation and partly in vertical section, showing a charge guide embodying the present invention supported in position to deliver a charge from a feeder into an underlying mold;

70 Fig. 2 is a relatively enlarged plan view of the improved charge guide alone;

75 Fig. 3 is a vertical section through the improved charge guide, the view being taken substantially along the line 3—3 of Fig. 2; and

Fig. 4 is an elevation of the inner face of the 80 combined front guard and fluid applying member of the improved guide.

The improved guide, generally designated G in the drawing, comprises an elongate vertical 85 back member 11 which is substantially wedge shaped in cross section, as best seen in Fig. 2. The rear portion of this back member 11 is formed with laterally extending ears or lugs 12 which may be clamped to a substantially vertical 90 supporting surface 15, Fig. 1, by washers 13 on bolts 14. The supporting surface 15 may be a side face of a cullet chute or trough 16, which is carried at the outer end of arm 17. The arm 17 is mounted for swinging movement within limits 95 about the axis of a vertical column 18. The bolts 14 may be loosened to permit vertical adjustment of the back member 11 on the supporting surface 15.

The front portion of the back member 11 has 100 a substantially plane front surface, indicated at 19, which constitutes the back wall of the charge guide. The side walls of the charge guide comprise the substantially vertical surfaces 20 and 21 respectively of opposed side members 22 and 23, which are attached to and cooperate with the back member 11.

105 These side members 22 and 23 have laterally extending attaching flanges 24 and 25 respectively disposed flatwise against the front faces of upper laterally extending ears or lugs 26 and lower laterally extending ears or lugs 27 on the front portion of the back member 11. The attaching flanges 24 and 25 have upper and lower lateral slots 28 and 29 respectively in their edge 110

portions, these slots being open at the outer edges of such attaching flanges and being adapted to accommodate the shanks of bolts 30 which extend through openings 31 in the upper and lower lateral ears 26 and 27 of the back member. The rear ends of these bolts 30 may be engaged by nuts 32. Springs 33 are disposed on the shanks of these bolts between the heads thereof and washers 34, which bear against the attaching flanges 24 and 25. The pressure of these springs on the washers 34, and hence on the attaching flanges 24 and 25, may be varied by adjusting the nuts 32. Preferably, this pressure is sufficient to hold the flanges firmly in place against the ears 26 and 27, and at the same time adapted to permit the side members 22 and 23 to be slid laterally, as a result of positively applied force, toward or away from each other, as required to adjust within limits the effective width of the charge guide.

Except for the specific improved mechanism just described for adjustably connecting the side members 22 and 23 of the charge guide with the back member of that guide, the parts which have been described so far are substantially the same as those of the charge guide of my aforesaid prior application Ser. No. 521,688.

As in the case of the charge guide of said prior application, the supporting mechanism for the present charge guide may be of suitable construction and provided with suitable adjustments and operating mechanism to permit vertical and angular adjustments of the charge guide to assure exact alignment of the charge guide with the outlet 35 of an associate feeder, designated generally F, at the proper time to receive a charge from the feeder and to permit swinging movement of the charge guide in register with an underlying mold, designated M, for the proper delivery of the charge to the mold when the latter is carried by a continuously moving table (not shown) or like carrier. The details of the adjusting and operating mechanism for the guide and of the supporting and operating mechanism for the mold form no part of the present invention, and therefore need not be illustrated or described herein. Any suitable mechanisms for these purposes may be employed, although I prefer to use mechanisms similar to those which are disclosed in my aforesaid pending application, Ser. No. 521,688.

The back member 11 of the improved guide is provided with an internal cooling chamber or space 36, Figs. 2 and 3. This cooling chamber 36 may be provided at its lower end with an inlet 37 and, adjacent to its upper end, with an outlet 38. The inlet and the outlet may be connected with any suitable fluid conducting means, whereby a cooling fluid may be supplied to the chamber 36 and circulated through the back member in a manner which is obvious. The cooling chamber or space 36 is shown in Fig. 3 as terminating somewhat above the level of the lower end of the back member 11, but it is obvious that this cooling space may extend substantially the full length of the back member or for any desirable part of such length.

A combined front guard and fluid pressure applying member is indicated at 39 in the drawing. As shown to advantage in Fig. 3, the member 39 is of elongate hollow form and has an internal chamber 40 extending substantially the full length of the member 39. The chamber 40 may be closed at its lower end and provided at its upper end with an inlet 41 adapted for connec-

tion with a fluid pressure supply pipe or tube 42.

The inner wall of the member 40 is formed at intervals throughout its length and width with downwardly inclined discharge orifices 43. These orifices 43 may be arranged in a plurality of vertical rows with the orifices of the respective rows staggered vertically, as shown in Fig. 4. Where there are three vertical rows of orifices as shown, the orifices of the middle row may be located in a vertical plane approximately midway between the side edges of the member 39, while the orifices of the side rows may be inclined downwardly and laterally outward so as to be located in divergent vertical planes, as best seen in Fig. 2. With this arrangement, jets of fluid from the orifices 43 will impinge obliquely against the side walls of the guide as well as against the back wall thereof when the guard and fluid applying member is supported at the front of the guide, as shown in Figs. 1 to 3, inc.

For supporting the member 39 in operative position at the front of the charge guide, the following mechanism may be employed. Forwardly extending lugs or ears 44 on one of the side members 22 or 23 (on the member 23 in the form shown) are provided with horizontal slots 45 which are open at the outer ends of the lugs 44. The lugs are spaced vertically a distance corresponding approximately with the distance between vertically spaced bosses 46 and 47 on the member 39. The outer faces of these bosses may be clamped firmly against the lugs 44 by means of cap bolts 48 which extend through the slots 45 and are threadedly engaged with the walls of suitable lateral openings in the bosses 46 and 47. Washers 49 preferably are disposed on the shanks of the cap bolts 48 between the heads thereof and the slotted portions of the lugs 44. By loosening the bolts 48, the shanks thereof may be slid along the slots 45 to adjust the position of the inner surface of the member 39 with respect to the back wall 19 of the charge guide. The bosses 46 and 47 are of sufficient lateral extent to locate the longitudinal median line of the member 39 approximately midway between the planes of the side walls of the guide.

The lugs 44 also provide a convenient means for manipulating the member 23 when it is desired to adjust such member laterally on the back member of the charge guide. A lug 50 or other handle may be provided on the member 22 to permit convenient lateral adjustment of the member 22 either coincidentally with adjustment of the member 23 or with respect to the latter. These lugs 44 and 50 may be grasped or tapped with a suitable implement to effect the desired adjustment of the width of the charge guide.

The surfaces 20 and 21 of the side members of the guide may be substantially straight from the lower ends of such members nearly to the upper ends thereof, the extreme upper end portions of such surfaces being curved or beveled, as indicated at 51 in Fig. 1. The inner wall of the member 39 likewise may curve upwardly and outwardly adjacent to its upper end, as indicated at 52. The flaring in this manner of the upper end of the charge directing space of the guide will aid in effecting proper entry of a falling charge, such as indicated at 53 in Fig. 1, into such space.

From the foregoing description of the various parts of the improved charge guide, the operation thereof will be readily understood.

When the charge guide is supported by any

suitable structure, preferably as hereinbefore has been indicated, below and in alignment with the outlet 35 of the feeder F, the charge delivered by the latter will fall axially downward into the 5 charge directing channel of the guide without any portion of the charge striking the upper edge of any of the walls of the charge guide. The charge will be directed by the walls of the guide downwardly into the underlying mold M, which 10 may be an inverted parison mold, as shown. If the mold is carried by a continuously moving carrier, the guide will be provided with suitable mechanism for moving it in register with the mold during the delivery of the charge to the 15 mold.

The contact of the charge with walls of the guide will be reduced to a minimum, such contact being along vertical lines. Undue or unequal chilling of the charge by the guide thus 20 will be obviated.

The cooling of the back member of the guide, which is the heavier and larger portion thereof, will prevent objectionable heating of such member and will tend to maintain the walls of the 25 guide, or at least the back wall of the guide, in a desirably cool condition. This cooling of the guide by the provision of the cooling space in the back member thereof may be supplemented by the application to the inner walls of the guide of 30 jets of air or air having oil entrained therewith or other cooling fluid from the orifices 43. Preferably, the fluid delivered from the orifices 43 is under sufficient pressure to prevent any forward deflection of any portion of the charge from a 35 desirable vertical path of movement through the charge guide into the underlying mold and will aid in directing the charge downwardly along such path. Of course, should abnormal circumstances cause a forward deflection of the charge 40 or of any portion thereof, the contact thereof with the inner wall of the guard 39 would restore the deflected portion of the charge to its proper path of movement and assure entry of the charge centrally into the cavity of the mold with which the 45 charge guide was aligned. The fluid discharging from the orifices 43 to the interior of the charge guide will tend to maintain a condition of uniform and desirable temperature at the places of contact between the glass and walls of the guide. 50 Furthermore, such fluid may lubricate the portions of the charge guide with which the falling charge contacts, so that the passage of the charge through the guide will be facilitated.

For these and other reasons, which will be apparent from the foregoing description, the improved charge guide affords facilities for directing a falling charge into an underlying mold accurately without impairment of the thermal condition or objectionable change of shape of the 60 charge.

It will be noted that the member 39, while serving as a front guard and fluid applying device for the guide, does not entirely close the guide at the front but on the contrary permits both a view of and circulation of air through the charge directing interior of the guide.

Also, the guard is quickly removable to permit access to the interior of the guide for any purpose and may be as quickly replaced when that purpose has been served.

It is to be understood that the invention may be embodied in various forms which may vary as to the construction, combination, and arrangement of the parts thereof without departing from the spirit and scope of the invention, which is not

to be limited except as required by a fair construction of the terms of the appended claims.

I claim:

1. In mold charge delivery apparatus, a substantially vertical charge guide comprising a back member and a pair of spaced side members attached to the back member and cooperating with the latter to produce a charge guiding channel, vertically spaced forwardly projecting lugs on one of said side members, said lugs having horizontal slots therein open at their outer ends, an elongate guard having laterally extending bosses adapted to bear against the slotted portions of said lugs, and attaching devices extending through the slots of said lugs and engaged with said bosses for supporting said guard at the front of said charge directing channel in parallel relation with the back wall thereof and approximately midway between the planes of the side members of said guide. 80

2. In mold charge delivery apparatus, a substantially vertical charge guide comprising a back member and a pair of spaced side members attached to the back member and cooperating with the latter to produce a charge guiding channel, vertically spaced forwardly projecting lugs on one of said side members, said lugs having horizontal slots therein open at their outer ends, an elongate guard having laterally extending bosses adapted to bear against the slotted portions of said lugs, and attaching devices extending through the slots of said lugs and engaged with said bosses for supporting said guard at the front of said charge directing channel in parallel relation with the back wall thereof and approximately midway between the planes of the side members of said guide, said guard also being adapted to discharge fluid under pressure into the charge directing channel of said guide at different places along the length of the latter. 90

3. In mold charge delivery apparatus, a charge guide for receiving a separated preformed falling mold charge of molten glass and for guiding said charge to an underlying charge receiver, said charge guide comprising a substantially vertical back member and a pair of substantially vertical side members, said back member and said side members having substantially plane inner surfaces and being relatively disposed so that the inner surfaces of the side members are located in spaced confronting relation each with respect to the other and each at approximately right angles with the inner surface of the back member, thus producing a substantially vertical channel of such character as to guide the falling charge by contact therewith along but three spaced vertical lines, and a removable substantially vertical elongate guard at the front of said vertical channel for preventing substantial forward displacement of the falling charge from its vertical path of movement in three-line contact with the inner walls of said channel, said elongate guard member being adapted to direct fluid under pressure into the space within said channel and against the walls thereof. 100

4. In mold charge delivery apparatus, a charge guide for receiving a separated preformed falling mold charge of molten glass and for guiding said charge to an underlying charge receiver, said charge guide comprising a substantially vertical back member and a pair of substantially vertical side members, said back member and said side members having substantially plane inner surfaces and being relatively disposed so that the inner surfaces of the side members are located in 110

spaced confronting relation each with respect to the other, and each at approximately right angles with the inner surface of the back member, thus producing a substantially vertical channel of such character as to guide the falling charge by contact therewith along but three spaced vertical lines, and a removable substantially vertical elongate guard at the front of said vertical channel for preventing substantial forward displacement of the falling charge from its vertical path of movement in three-line contact with the inner walls of said channel, said elongate guard member having

an internal chamber for the reception of a fluid and having in its inner wall substantially vertical rows of downwardly and inwardly inclined orifices for discharging fluid from said internal chamber into the interior of said channel, certain of said orifices lying in a vertical plane extending approximately midway between the side walls of said channel and other of said orifices lying in vertical planes which diverge toward the side walls of said channel.
